ELASTIC FLUID POWER PLANT

Frederick Nettel, Manhasset, and John Kreitner,
New York, N. Y.

Application December 9, 1942, Serial No. 468,380

6 Claims. (Cl. 60—59)

The present invention relates to elastic fluid power plants, more especially to such including a plurality of gas turbines arranged in parallel as regards the flow of the fluid through them, a source of compressed gas for the turbines and heating means for indirect heating of said compressed gas through heat transfer.

In plants with a useful power turbine and a compressor driving turbine arranged in parallel, partial load operation predicates changes in the quantities of working air or gas fed to the respective turbines; this is done in known plants by flow regulating means immediately in front of the inlets to the turbines. Such means are exposed to the highest temperatures prevailing in the systems and therefore expensive to build and to maintain.

It is an object of this invention to avoid this disadvantage.

It is another object to utilize efficiently the heat in the air or gas discharged from the turbines, and it is a further specific object to provide arrangements specially suited to the type of fuel burning means employed.

These and other objects are achieved by the combination of some or all of the following steps:

(a) Bifurcating the stream of the compressed working fluid at a point before it enters the heating means,

(b) Keeping the two branch streams separate during their passage through the regenerative preheating and fuel burning heating means to the inlets of the two turbines arranged in parallel,

(c) Providing means for controlling the flow resistance in one or both of said branch streams, these means being arranged in front of all heating means,

(d) Burning fuel for producing a heating gas stream passing through the high temperature side of the heating means,

(e) Leading expanded working fluid discharged from one or both said turbines into said heating gas stream where the temperature of said stream is substantially equal to or lower than the temperature of the expanded fluid at the point of its entrance to the heater,

(f) Withdrawing a branch stream from said heating stream, where it has been cooled by heat transfer to a temperature suitable for the type of fuel burning means employed, and using the free oxygen of this branch stream for the combustion of the fuel,

(g) Bifurcating the stream of combustion gases issuing from the combustion chamber in

two branch streams, leading them separately through the heater, and providing means for controlling the flow resistance in one or both of said branch streams, these means being arranged behind all heating means,

(h) Controlling simultaneously the flow of the two branch streams of compressed working fluid, and the flow of the two branch streams of combustion gases in heat transfer relationship to the first said streams,

(i) Controlling jointly the flow of one branch stream of compressed working fluid and the flow of the branch gas stream in heat transfer relationship thereto in definite relationship to the heating end temperature of the compressed working fluid in first said branch stream. For a consideration of what we believe to be novel and our invention reference is made to the following description and the claims appended thereto in connection with the accompanying drawings in which by way of non-limiting examples

Fig. 1 shows an embodiment of a plant for utilizing pulverized coal as fuel.

Fig. 2 represents an alternative embodiment for utilizing ordinary coal or other solid fuel on a travelling grate and control means for such plant.

Fig. 3 indicates an alternative arrangement to Fig. 1 with means for admixing colder compressed air to the hot air at the inlets to the air turbines.

Referring now to Fig. 1, the illustrated arrangement comprises a compressor 10 having an inlet conduit 11 for receiving air from the atmosphere, conduit 12 for discharging compressed air. This air enters surface type heater 13 via three-way valve 14 and branch conduits 15 and 16. The headers 17 and 18 of the heating device are connected by tubes for the compressed air and divided by walls 17' and 18', so as to keep the branch streams entering through conduits 15 and 16 separate. From header 18 conduits 19 and 20 lead the air to the inlets of turbines 21 and 22 respectively, in which said air is expanded and discharged through conduits 23 and 24, joining into conduit 25, and thence into the gas channel of heater 13 at 26, where the temperature is just about equal to that of the entering air. An exhaust conduit 31 allows the gases and air to escape to the atmosphere. Between points 26 and exhaust conduit 31 conduit 27 is disposed allowing the withdrawal of the mixture of combustion gas and air. The conduit, in which fan 28 is interposed, is connected to the combustion chamber 30 via burner for pulverized coal 29. This

burner receives coal from valved pipe 32 from a source not shown.

As indicated in the drawing, turbine 22 is mechanically coupled to compressor 10, while turbine 21 is so coupled to a power consuming device which in the example is an electric generator 33. A motor 34 of any kind is provided for starting the plant.

The plant operates as follows:

At maximum load valve 14 is adjusted to allow 10 unrestricted air flow to conduits 15 and 16 which are dimensioned to allow passage for the air quantities required by the turbines 21 and 22 respectively. The air-gas mixture entering combustion chamber 30 via conduit 27 and fan 28, 15 serves as combustion supporting medium for the pulverized coal fed through pipe 32. The resulting hot gases of combustion are led through the heater, as indicated by the dotted line, substantially in counterflow to the compressed air passing through the tubes of the heater, being thereafter discharged to the atmosphere through conduit 31.

Only a portion of the air-gas mixture from the heater is used for combustion; the remainder passes through the rest of the heater which serves simultaneously as recuperator for the heat in the air discharged from the turbines.

The point in the gas stream to which conduit 27 is connected is so selected, that the temperature of the air-gas mixture is suitable for the burner.

At other loads valve 14 is adjusted to vary the air quantities flowing to the respective turbines. The rate of fuel supply is adjusted by valve in pipe 32, the rate of admittance of the combustion supporting medium to the combustion chamber by adjusting the speed of fan 28. The temperature of either branch stream of compressed air leaving the heating means may be controlled, as known in the art, by admitting unheated compressed air branched off in front of the heating means. Fig. 3 shows such an arrangement suitable for embodiment in plant as per Fig. 1. A conduit 50 is branched off from the compressor discharge conduit 12 and connected via control valves 51 and 52 to both conduits 19 and 20 respectively. If the air temperature in either of these latter conduits exceeds a desirable value, valves 51 and/or 52 are operated to admix air from conduit 12.

Fig. 2 shows an embodiment suited for burning coal on a travelling grate with forced draft. The operation is generally similar to that of arrangement as per Fig. 1; the main difference lies in the design of the heater and the control of the plant.

Instead of the coal burner, grate 29' is disposed in combustion chamber 30, from which the combustion gases are led through the heater in two separate parallel streams as indicated by dotted lines, and discharged also separately through separate conduits 31 and 31'. The combustion supporting medium is withdrawn from conduit 31' via conduit 28', fan 28'' and damper 28''' to the combustion chamber. Air from the turbines is led into the two separate gas streams by two separate conduits 25 and 25', at points where the gas temperatures are just about equal to the temperatures of the said air coming from the turbines.

For purposes of load control, valve 14 is provided with control lever 35 which is connected by lever and rods 36 to damper 37 disposed within conduit 31. The fulcrum of lever 36 is supported by bellows 38' of a vapor-pressure type thermostat

38 disposed in the inlet conduit to turbine 21 and connected to it by pipe 39. Furthermore the grate is equipped with a slide 40 for adjusting the thickness of the coal layer on the grate. This slide is connected by lever 41 to rod 42 and to the bellows 43 of a thermostat 44 disposed in the inlet conduit to turbine 22 and connected to it by pipe 45. Rod 42 is also connected to the beforementioned hand lever 35 by rods and bell cranks 46 as indicated.

The control operates as follows:

If the plant operates at partial load, in which case the air flow to conduit 15 is restricted by valve 14, and a higher load is desired, lever 34 15 is moved anticlockwise, thus admitting more air to turbine 21. To meet the higher heating requirements in the upper tubes of the heater, damper 37 is opened more, being operated by rods and lever 36. Opening of damper 37 reduces the flow resistance in conduit 31 and more gases from the combustion chamber are available for heating the upper tubes. The necessary increase in fuel supply for the higher load is initiated also by hand lever 35 acting on rods and cranks 46, 20 causing rod 42 to lift lever 41 round the supporting point of the bellows 43 as fixed point, thus raising slide 40 for an increased coal supply to the grate, and raising damper 28''' for admitting more combustion supporting medium to the combustion chamber.

The purpose of thermostat 38 and bellows 38' is to prevent the temperature at the inlet to turbine 21 from rising inadmissibly. In such case the bellows 38' expand, moving the left hand end 35 of lever 36 upwards, thus tending to close damper 37 a little, until the temperature at 38 is again normal.

Thermostat 44 and bellows 43 serve the same purpose for turbine 22. If the temperature at 40 conduit 20 should rise too high, bellows 43 expand and move lever 41 round point 41' as fixed point, so that slide valve 40 and damper 28''' tend to close somewhat, with the result that less coal is burned and the temperature in conduit 45 20 restored to normal.

It is evident that by avoiding exposure of all flow control means to high temperatures, greater reliability in operation is attained, quite apart of the lower costs for these parts.

50 It is immaterial for this invention what types turbines or compressors are used, whether or not intercooling of the air before or during compression, and reheating during expansion are employed.

55 While preferred illustrative embodiments of the invention have been shown and described, it is to be understood that various modifications in the details of construction and mode of operation may be resorted to without departing from the spirit of the invention within the definition of the appended claims.

What we claim is:

1. In combustion turbine power plants including a compressor driving turbine and a useful power turbine, said two turbines being mechanically independent of each other and arranged in parallel with respect to the flow of the working fluid, the combination of fuel burning means for creating a heating gas stream, conduit means for said heating gas stream, heating surfaces arranged to transfer the heat of said gas stream onto the compressed working fluid, conduit means for bifurcating the stream of the compressed working fluid in front of its inlet to said heating means, conduit means for leading two separate branch

streams of the compressed working fluid past said heating surfaces into said two turbines, means for controlling the flow resistance of at least one of said branch conduits disposed in front of its inlet to said heating means, and conduit means connecting the outlet of at least one of said turbines to a point of said heating gas conduit where the gas temperature is substantially equal to or lower than the temperature of the expanded working fluid prior to its admixture to the gas stream.

2. In combustion turbine power plants according to claim 1, using air as working fluid, conduit means connecting the combustion air inlet of said fuel burning means with said conduit means for heating gas at a point past said heating surfaces.

3. In combustion turbine power plants according to claim 1, using air as working fluid, conduit means connecting the combustion air inlet of said fuel burning means with that intermediate point of said conduit means for the heating gas stream where said stream has reached by heat transfer a temperature permissible for said fuel burning means.

4. In combustion turbine power plants including a compressor driving turbine and a useful power turbine, said two turbines being mechanically independent of each other and arranged in parallel with respect to the flow of the working fluid, the combination of fuel burning means for

creating a heating gas stream, conduit means for bifurcating said heating gas stream, conduit means forming two separate branch streams of said heating gas, heating surfaces arranged to transfer heat of said branch streams onto the compressed working fluid, means for controlling the flow resistance of at least one of said branch conduits disposed past said heating surfaces, means for bifurcating the stream of the compressed working fluid disposed in front of its inlet to said heating surfaces, conduit means forming two separate branch streams of the compressed working fluid, each being arranged in heat exchange relation to one of said branch streams of the heating gas, and means for controlling the flow resistance of at least one of said branch conduits for the compressed working fluid, said controlling means being disposed in front of the inlet to said heating means.

5. In combustion turbine power plants according to claim 4, conduit means connecting the outlet of each turbine to an intermediate point of that heating gas branch conduit which is in heat exchange relation to the compressed working fluid branch conduit connected to said same turbine.

6. In combustion turbine power plants according to claim 4, means for joint flow control in two branch conduits disposed in heat exchange relation to each other.
